VALVE FOR FEED WATER HEATERS

Emanuel Rawson, Chicago, Ill., assignor to The Superheater Company, New York, N. Y.

Application December 4, 1937, Serial No. 178,053

7 Claims. (Cl. 122—441)

This invention relates to feed water heaters and particularly to arrangements for controlling the supply of live steam thereto for heating the feed water.

As an illustrative embodiment, the invention will be described in conjunction with a locomotive feed water heater which is normally supplied with exhaust steam from the locomotive engines and/or auxiliaries. The heater is supplied with live steam from the locomotive boiler through piping having a control valve provided with operating means responsive to the pressure of steam actuating the feed water pump. The transmission of this pressure to the control valve operating means is regulated by a pilot valve itself associated with means responsive to the pressure of steam operating the locomotive engine. The arrangement is such as to assure that while the pump is operating the heater will be supplied with live steam if the engine is stopped or throttled to such an extent that the supply of exhaust steam is inadequate to heat the feed water. Another feature of the invention is that the control valve closes promptly when the supply of exhaust steam becomes adequate or the pump is shut down.

Other features and advantages of the invention will be apparent upon consideration of the following detailed description of an illustrative embodiment when read in conjunction with the appended claims and the accompanying drawings in which:

Fig. 1 is a diagrammatic side elevational view of a locomotive embodying the invention;

Fig. 2 is an enlarged sectional view of the control valve; and

Fig. 3 is a similar view of the pilot valve.

Referring to Fig. 1, the numeral 10 designates the boiler of a locomotive provided with a feed water heater 11 supplied with feed water by a pump 12. Pump 12 is operated by live steam supplied from the locomotive turret 13 through a steam line 14 controlled by a throttle valve 15. The heater 11 is normally supplied through a pipe 16 with exhaust steam from the locomotive engines 17. At times when the supply of exhaust steam is inadequate, during operation of the pump 12, live steam is supplied to the heater 11 from the boiler 10 through piping 20 having a control valve 21 interposed therein.

As shown in Fig. 2, the control valve 21 comprises a casing 22 provided with a valve member 23 biased to its closed position by a non-adjustable spring 24. Associated with the valve member 23 is a piston cylinder 25 containing a piston

26 arranged to open the valve. The piston 26 has an extension 27 of reduced diameter in communication through an orifice 28 with the outlet chamber 29 of the valve so that the pressure of steam in chamber 29 may assist in closing the valve, the choke 29a that regulates the flow of steam to the heater being located on the outlet side of valve 21 to build up maximum pressure in chamber 29 so as to close the valve quickly. The piston cylinder 25 is connected by a pipe 30, 10 31 to the steam line 14 for the feed water pump 12. A pilot valve 32 interposed into pipe 31 regulates the supply of steam to the piston cylinder 25 for subjecting the piston 26 to the pressure of steam operating the pump 12. The pipe 31 has an extension 33 connected with the exhaust steam chamber of the feed water heater, a choke 34 having an opening of materially smaller area than the passage through the pilot valve 32 being provided to restrict the flow of 20 steam from the pump steam line 14 to the heater 11.

The pilot valve 32, as shown in Fig. 3, consists of a casing containing a valve member 35 urged towards its open position by an adjustable spring 36. The valve member 35 is in the form of a plunger having one end extending into a chamber 37 which is connected by a pipe 38 to the engine steam pipe for subjecting the plunger to the pressure of steam operating the locomotive 30 engine 17.

The operation is as follows: When the pump 12 is placed in operation by opening the valve 15, steam from the pump steam line 14 passes through the pipe 31 to the inlet chamber 39 of the pilot valve 32. With the locomotive engines 17 operating at such a rate that the supply of exhaust steam through the pipe 16 is adequate to heat the feed water in heater 11, the pressure of steam operating the engine is communicated through the pipe 38 to the chamber 37 and acts on the valve member 35 against the force of spring 36 to maintain it closed. Inasmuch as the supply of steam to the piston cylinder 25 through the pipe 31 is cut off at this time by 45 the closed pilot valve 32, the control valve 21 is maintained closed by the spring 24 plus boiler pressure acting on the top of valve member 23.

In the event that the locomotive is stopped or the engines 17 are throttled to such an extent 50 that the supply of exhaust steam is inadequate to heat the feed water, the pressure communicated to chamber 37 through pipe 38 decreases and the spring 36 acts to move the valve member 35 to its open position. When the pilot valve 32 opens, 55

steam passes from the pump steam line 14 through the pipe 31 and extension 33 to the heater 11, the amount of steam flowing to the heater being restricted by the choke 34 so that 5 pressure is built up in the piston cylinder 25 which is connected to the pipe 31 by the pipe 30. Thus, the pressure of steam operating the pump 12 is communicated to the piston cylinder 25 from the pump steam line 14 and acts on the piston 26 10 against the force of spring 24 and boiler pressure on valve 23 to move the valve member 23 to its open position so that live steam passes from the boiler 10 through the piping 20 into the feed water heater 11.

15 When the locomotive again operates at a rate such that the supply of exhaust steam is adequate to heat the feed water, the pilot valve 32 is again closed by the engine pressure thus cutting off the flow of steam from the pump steam line 14 to the 20 piston cylinder 25 so that the control valve 21 may close. If, alternatively, the valve 15 is closed to stop the pump, the control valve piston 26 is relieved of pressure from the pump steam line 14. In either event, when the piston 26 is relieved 25 of the pressure of steam operating pump 12, the spring 24 acts on the valve member 23 to close it, being assisted by the pressure of live steam in chamber 29 acting on the reduced portion 27 of the piston through the orifice 28. As the valve 30 member 23 is moved towards its closed position, the corresponding movement of the piston 26 expels any steam remaining in the piston cylinder 25 through the pipe 30, extension 33 and choke 34 into the heater 11, or elsewhere if desired, so that valve 32 closes quickly.

Although an illustrative embodiment of the invention has been shown and described in detail herein, it is to be understood that many changes and variations may be made without departing 40 from the invention, and accordingly it is intended to include all such changes and variations within the scope of the appended claims.

What I claim is:

1. In a boiler feed water system having a heater 45 normally supplied with exhaust steam from an engine deriving steam from the boiler, a pump supplying water to the boiler through said heater, a throttle controlled steam line from the boiler to said pump, piping connecting the boiler to said heater for supplying live steam thereto, and a control valve in said piping; means for closing 50 said control valve; a piston cylinder associated with said valve; a pipe connecting said pump steam line and said cylinder; a pilot valve in said 55 pipe; means responsive to the pressure of steam operating said engine so arranged as to close said pilot valve when the supply of exhaust steam is adequate to heat the feed water in said heater; means acting on said pilot valve so as to open it for admitting steam to said pipe 60 for admitting steam to said pipe and cylinder when the supply of exhaust steam is inadequate to heat the feed water in said heater; and a piston in said cylinder responsive to the pressure of steam operating said pump and adapted to 65 open said control valve when said pump is operating while said pilot valve is open due to inadequacy of the supply of exhaust steam to heat the feed water in said heater.

2. In a boiler feed water system having a 70 heater normally supplied with exhaust steam from an engine deriving steam from the boiler, a pump supplying water to the boiler through said heater, a throttle controlled steam line from the boiler to said pump, piping connecting the 75 boiler to said heater for supplying live steam

thereto, and a control valve in said piping; a piston cylinder associated with said valve; a pipe connecting said pump steam line and said cylinder; a pilot valve in said pipe; means responsive to the pressure of steam operating said engine so 5 arranged as to close said pilot valve when the supply of exhaust steam is adequate to heat the feed water in said heater; means acting on said pilot valve so as to open it for admitting steam to said pipe and cylinder when the supply of exhaust steam is inadequate to heat the feed water in said heater; a piston in said cylinder responsive to the pressure of steam operating said pump and adapted to open said control valve when said pump is operating while said pilot 15 valve is open due to inadequacy of the supply of exhaust steam to heat the feed water in said heater; means acting on said control valve to close it when the pressure of steam operating said pump falls below a predetermined pressure; and a restricted vent for said cylinder for exhausting the latter of steam as said valve closes to permit quick closing of said control valve by said means.

3. In a boiler feed water system having a 25 heater normally supplied with exhaust steam from an engine deriving steam from the boiler, a pump supplying water to the boiler through said heater, a throttle controlled steam line from the boiler to said pump, piping connecting the boiler 30 to said heater for supplying live steam thereto, and a control valve in said piping; a piston cylinder associated with said valve; a pipe connecting said pump steam line and said cylinder; a pilot valve in said pipe; means responsive to the pressure of steam operating said engine so arranged 35 as to close said pilot valve when the supply of exhaust steam is adequate to heat the feed water in said heater; means acting on said pilot valve so as to open it for admitting steam to said pipe 40 and cylinder when the supply of exhaust steam is inadequate to heat the feed water in said heater; a piston in said cylinder responsive to the pressure of steam operating said pump and adapted to open said control valve when said 45 pump is operating while said pilot valve is open due to inadequacy of the supply of exhaust steam to heat the feed water in said heater; means subjecting said piston to the pressure of steam passing through said control valve and piping so 50 arranged as to tend to close said control valve; and spring means acting in conjunction with said last means to close said control valve.

4. In a boiler feed water system having a 55 heater normally supplied with exhaust steam from an engine deriving steam from the boiler, a pump supplying water to the boiler through said heater, a throttle controlled steam line from the boiler to said pump, piping connecting the boiler 60 to said heater for supplying live steam thereto, and a control valve in said piping; a piston cylinder associated with said valve; a pipe connecting said pump steam line and said cylinder; a pilot valve in said pipe; means responsive to the pressure of steam operating said engine so arranged 65 as to close said pilot valve when the supply of exhaust steam is adequate to heat the feed water in said heater; means acting on said pilot valve so as to open it for admitting steam to said pipe 70 and cylinder when the supply of exhaust steam is inadequate to heat the feed water in said heater; a piston in said cylinder responsive to the pressure of steam operating said pump and adapted to open said control valve when said pump is 75

- operating while said pilot valve is open due to inadequacy of the supply of exhaust steam to heat the feed water in said heater; means acting on said control valve to close it when the pressure of steam for operating said pump falls below a predetermined pressure; and a connection between said heater and cylinder for exhausting the latter of steam to permit quick closing of said valve by said means.
5. In a boiler feed water system having a heater normally supplied with exhaust steam from an engine deriving steam from the boiler, a pump supplying water to the boiler through said heater, a throttle controlled steam line from the boiler to said pump, piping connecting the boiler to said heater for supplying live steam thereto, and a control valve in said piping; means for closing said control valve; a piston cylinder associated with said valve; a pipe connecting said pump steam line to said heater; a pilot valve in said pipe; means responsive to the pressure of steam operating said engine so arranged as to close said pilot valve when the supply of exhaust steam is adequate to heat the water in said heater; means 10 acting on said pilot valve so as to open it for admitting steam to said pipe when the supply of exhaust steam is inadequate to heat the feed water in said heater; a connection from said pipe to said cylinder at a point between said pilot valve and said heater; a piston in said cylinder arranged to open said control valve; and a choke in said pipe at a point between said heater and said connection to said cylinder for restricting the flow of steam from said pump steam line to 15 said heater and for building up steam pressure in said cylinder to cause the piston therein to open said control valve for supplying live steam to said heater through said piping; and means acting on said control valve so as to close it when steam 20 operating said pump falls below a predetermined pressure and causing the steam in said cylinder to be exhausted into said heater through said connection and pipe.
7. In a boiler feed water system having a 25 heater normally supplied with exhaust steam from an engine deriving steam from the boiler, a pump supplying water to the boiler through said heater, a throttle controlled steam line from the boiler to said pump, piping connecting the boiler 30 to said heater for supplying live steam thereto, and a control valve in said piping; means for closing said control valve; steam operated means for opening said control valve; a steam pipe for supplying said means; a pilot valve in said steam 35 pipe; means responsive to the pressure of steam operating said engine so arranged as to close said pilot valve when the supply of exhaust steam from said engine is adequate to heat the water passing through said heater; and means acting on said 40 pilot valve and operative to open it, when said supply of exhaust steam is inadequate to heat the feed water in said heater, for supplying steam to said operating means for said control valve to open the latter and supply live steam to said 45 heater through said piping.
6. In a boiler feed water system having a heater normally supplied with exhaust steam from an engine deriving steam from the boiler, a pump supplying water to the boiler through said heater, a throttle controlled steam line from the boiler to said pump, piping connecting the boiler to said heater for supplying live steam thereto, and a control valve in said piping; a piston cylinder associated with said valve; a pipe connect-
